UNITED STATES PATENT OFFICE.

JOHN P. GORDON, OF COLUMBUS, OHIO.

COMBINED STORM APRON AND HOOD.

SPECIFICATION forming part of Letters Patent No. 726,906, dated May 5, 1903.

Application filed January 2, 1902. Serial No. 88,020. (No model.)

To all whom it may concern:

Be it known that I, JOHN P. GORDON, a citizen of the United States, residing at Columbus, in the county of Franklin and State of Ohio, have invented a certain new and useful Improvement in a Combined Storm Apron and Hood, of which the following is a specification.

My invention relates to the improvement of vehicle storm aprons and hoods; and the objects of my invention are to provide a combined storm apron and hood of improved construction which will close the forward portion of a vehicle and completely protect the occupants against the entrance of rain or snow, to so construct my improved apron and hood as to adapt it to fit on buggy tops and dashes of different sizes, and to produce other improvements the details of which will be more fully pointed out hereinafter. These objects I accomplish in the manner illustrated in the accompanying drawings, in which—

Figure 1 represents a buggy body and top having my improved apron and hood thereon, the lower portion of the same being broken away to indicate the manner of connecting the same with the dash. Fig. 2 is a detail view in perspective, illustrating the manner of connecting my improved protector or apron with the vehicle bow side arms. Fig. 3 is a detail view in perspective of the adjustable top straps of the apron. Fig. 4 is a similar view of the adjustable bottom strap, and Fig. 5 is a transverse section through the upper portion 35 of the hood.

Similar numerals refer to similar parts throughout the several views.

In producing my improved apron and hood I form the body thereof of a single piece of waterproof material, and for the sake of convenience in description I will refer to the same as consisting of central and side portions 1 and 2; the central portion 1 being designed, as indicated in Fig. 1 of the drawings, 40 to cover the front of the vehicle, the upper or top edge portion thereof being adapted to be held in the manner hereinafter described in connection with the forward transverse top bow of the buggy-top, and the lower part 45 of said central portion being engaged with the dash of the vehicle. From this central portion 1 depend the side portions 2, the rear

edges of the latter being adapted to extend within or be overlapped by the side curtains 3 of the buggy-top. As indicated in Fig. 1 55 of the drawings, the side portions 2 are formed with extensions 2^a, which depend below the central or front portion 1. The upper edge of the front 1 is formed with a transverse casing, such as is indicated more clearly at 4 in Fig. 5, and through this casing passes a strap 6, which comprises a central rubber or elastic section 7, with which are united leather end sections 8, each of said end sections having extending therefrom a metal hook 9. The 60 leather portions 8 of the strap 6 are sewed or otherwise united with the casing 4, while the central portion of the casing, which embraces the rubber section 7, is Shirred, as indicated at 10. The end hooks 9 of the strap 6 are, as 70 indicated in Fig. 1, adapted to be movably engaged with the upper and forward top joint-pins 11 of the buggy-top. The lower portion of the front is, as prescribed for the upper portion, provided with a casing, the greater 75 portion of which is shirred, as indicated at 12, and through this casing passes an elastic strap-section 13, the latter having comparatively short leather terminations 14, with which are connected hooks 15, these hooks 80 being adapted to engage the ends of the dash 16 when the shirred portion 12 is drawn down partially over said dash. In order to connect the side portions 2 of the curtain with the buggy-top, I secure to each of said side portions on its inner side a strap 17, the outer end of which is adapted to be adjustably connected with a buckle 18, which is affixed to a yoke-like spring-clamp 19, this clamp adapted to be made to engage one of the forward bow side 90 arms 20 in the manner indicated more clearly in Fig. 2. As indicated at 21, the front portion 1 of the curtain may be provided with suitable windows or outlook-openings and with a suitably-placed rein-outlet having a 95 flap or cover 22.

From the construction shown and described it will be seen that both the front and sides of the forward opening or entrance to the vehicle are closed by my improved hood and curtain, and that owing to the employment of the hook-carrying straps at the upper and lower edges of the front portion 1 and the construction of these straps with elastic center

sections my improved apron and hood may be employed on buggy tops and dashes of different widths, the elastic operating to take up any slack or fullness in the goods forming the curtain. It will be understood that by pulling outward on the strap 17 the lips of the spring-clamps 19 will open by engagement with the bow side bars 20, permitting said clamps being readily withdrawn from said bars. As indicated in Fig. 1 of the drawings, the side extensions 2^a are adapted to depend on the outer side of the vehicle-body, which is indicated at 25, thus insuring protection against the entrance of rain at the sides of the vehicle-entrance.

Having now fully described my invention, what I claim, and desire to secure by Letters Patent, is—

1. A device of the character described, comprising a front section, opposite side sections extending rearwardly from the front section, the top and bottom edges of the front being beaded and shirred, elastic straps run through the beads and terminally secured thereto, the intermediate portions of the straps being free, and hooks secured to the ends of the straps

and projected externally of the beads at the ends thereof and beyond the edges of the front section for engagement respectively with forward top joint-pins of a vehicle-top and the opposite upright end edges of a dash. 30

2. A device of the character described, comprising a front section, opposite side sections extending rearwardly from the front section, the top and bottom edges of the front being beaded and shirred, elastic straps run through the beads and terminally secured thereto, the intermediate portions of the straps being free, hooks secured to the ends of the straps and projected externally of the beads at the ends 35 thereof and beyond the edges of the front section for engagement respectively with forward top joint-pins of a vehicle-top and the opposite upright end edges of a dash, straps secured to the rear edge portions of the side sections, and substantially U-shaped spring-clips secured to the straps with their open ends projected rearwardly. 40

JOHN P. GORDON.
